ATTY.

UNITED STATES PATENT OFFICE.

JOSEPH G. HUTCHINSON, OF ATTLEBOROUGH, MASSACHUSETTS.

DESIGN FOR A CIGAR AND ASH RECEIVER.

SPECIFICATION forming part of Design No. 25,121, dated February 4, 1896.

Application filed November 20, 1895. Serial No. 569,586. Term of patent 7 years.

To all whom it may concern:

Be it known that I, JOSEPH G. HUTCHINSON, a citizen of the United States, and a resident of Attleborough, in the county of Bristol and State of Massachusetts, have invented and produced a new and original Design for a Cigar and Ash Receiver, of which the following is a specification, reference being had to the accompanying drawings, illustrating the same.

10 Figure 1 is an elevation of a cigar and ash receiver, showing my design. Fig. 2 is a plan view of the same, these two views being deemed necessary to fully illustrate my design.

15 My design consists of a base having eccentrically-curved outlines, a circular receiver at the forward upper end of said base, having an upwardly-extending circumferential rim, a reversely-curved post extending upwardly 20 from the rear portion of said base, and a receiver of curved cross-section connected to the upper end of said post and arranged parallel with said base.

A is the base-plate, which has curved outlines, not true circles. B is the reversely-curved post extending upwardly from said base. C is the cigar-receiver, which is cylindrically curved and projects outwardly from the upper end of said post B over and parallel with said base A, and a receiver D arranged at the forward upper end of said base A and having a circular outline or circumference and an upwardly-projecting circumferential rim.

25 I claim and desire to secure by Letters Patent—

The design for a cigar and ash receiver, substantially as shown and described.

In testimony whereof I have hereunto set my hand, in presence of two witnesses, this 30 18th day of November, 1895.

JOSEPH G. HUTCHINSON.
